1818X

W. EDWARDS.
TANNING.

Patented Oct. 19, 1812.

1818X

William Edwards, Boston, Mass. Oct 19, 1818.

The Schedule referred to in this Bill is as follows, and marking part
of the same, containing a description in the words of the said
William Edwards, himself, of his improvement in tanning.

This invention consists of a cylindrical heater made of
brick. It must be drawn or composition of metal. This should be
round, contracted at the mouth in order conveniently to insert
it in the end of a vat or sack, from the mouth for three feet
it should be fifteen inches in diameter in order to receive the
fuel. At three feet from its mouth it should be contracted to the
size of a common stove pipe, which should be extended the
length of the vat which is to receive it, a right angle to be then
formed and the pipe extended above the top of the vat, when
the vat is filled with bark or tan and with water by making
a fire in the large part of the heater, heat will be produced in the
vat which is as much used in the process of tanning by extract-
ing all the tannin contained in the bark & soaping the tannin
away, to completely saturate the hide with the tanning principle
contained in the bark.
